UNITED STATES PATENT OFFICE.

ADOLPHUS C. MCCLURE, OF KEITHVILLE, LOUISIANA.

AUTOMATIC REPEATING FIREARM.

1,075,431.

Specification of Letters Patent.

Patented Oct. 14, 1913.

Application filed December 17, 1912. Serial No. 737,307.

To all whom it may concern:

Be it known that I, ADOLPHUS C. MCCLURE, a citizen of the United States, residing at Keithville, in the parish of Caddo and 5 State of Louisiana, have invented new and useful Automatic Repeating Firearms, of which the following is a specification.

The present invention is especially applicable to a shoulder piece, such as a repeating rifle or shot gun.

The primary object of the present invention is the provision of a breech block projecting and locking means disposed within the receiver of the fire arm for automatic release, due to the recoil from the explosion of a cartridge within the breech of the barrel and the effect thereof upon the breech block.

A further object of the present invention 20 is the provision of a manual controlling means for retracting the breech block to eject an unused shell or for the introduction of the first loaded shell within the breech of the barrel.

A still further object of the invention 25 is the provision of a novel means controllable manually for rendering the elevator mechanism inactive during the manual retraction and projection of the breech block.

A still further object of the present invention is the provision of a means controlled through said manual means for rendering the elevator mechanism inactive and 35 locking the breech block open, or placing the trigger at "safety" and also for rendering the manual breech block controlling means active or inactive selectively.

With the foregoing and other objects in 40 view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

In the drawings Figure 1 is a side elevation of an automatic fire-arm made according to and embodying the present invention, the removable plate of the receiver being detached with the breech block and locking mechanism in breech closing position. Fig. 2 is a longitudinal sectional view through the receiver and the adjacent por-

tion of the stock showing the breech block and locking mechanism in the farthest retracted position due to the recoil action of the cartridge thereupon when automatically 60 operated. Fig. 3 is a side elevation taken from the opposite side to Fig. 1 with the portion of the stock adjacent the receiver shown in section and with the manually controlled means for retracting the breech 65 block in full retracted position. Fig. 4 is a section taken on line 4-4 of Fig. 3. Fig. 5 is an enlarged longitudinal sectional view through the forward portion of the receiver, the cartridge elevator and the 70 magazine holding tube and a portion of the magazine, the parts being in the position when the breech block is sealing the breech of the barrel. Fig. 6 is a view partially in elevation and partly in section, the 75 sectional portion being a longitudinal horizontal sectional view through the exit end of the magazine tube and detachable magazine. Fig. 7 is a cross section taken on line 7-7 of Fig. 5. Fig. 8 is an enlarged detail 80 sectional view of the two intermediate pivoted members of the breech block locking and projecting mechanism. Fig. 9 is a detail view of the exit end of the flexible and detachable magazine with the parts in the 85 position they assume when filled with cartridges. Fig. 10 is an enlarged detail perspective view of the breech block, hammer and pivoted sections of the breech block operating mechanism. Figs. 11, 12, 13, 14, 90 15, 16, 17, 18, 19, 20, 21, 22, 23, 24, 25 and 26 are detail views of the various parts connected to and carried by the receiver, detached therefrom. Fig. 27 is a plan view 95 of the removable cover of the receiver. Fig. 28 is a cross section through the receiver and breech at the rear of the elevator, showing the lock for the breech block.

Referring to the drawings, the numeral 1 designates the stock, which has connected thereto the metal receiver 2 which is provided with the reduced recessed portion 3 at the lower portion of the hand grip thereof, the same being open as at 4 for the reception of the detachable and slotted closure 105 5, the purpose of which will presently appear. In one of the side walls of the receiver 2 an opening 6 is provided for the reception of the closure 7, the detail of which is clearly shown in Fig. 27, the same 110 being provided at its forward edge with the recessed portions 8 and 9 respectively, the

recessed portion 8 being for the direction of the ejected shells while the recessed portion 9 constitutes the trap opening for the introduction of the cartridges to the magazine, as will presently appear.

The slotted portion or aperture 10 is provided in the receiver 2 in the forward end 11 thereof and coacts with the slotted portion 9 of the closure 7 for the introduction of the cartridges into the inner end of the magazine holding tube 13. The barrel 12 and the magazine 13, as clearly shown in Figs. 1, 2 and 5, fit snugly against each other and are insertible within the socketed end 14 of the sleeve 11 of the receiver 2, the oppositely disposed flat springs 15 and 16 being carried by the receiver at this portion and for contact with the upper and lower portions of the barrel and magazine tube respectively to resiliently retain these members within the receiver. The adjacent faces 17 and 18 respectively of the barrel 12 and magazine 13 are flattened and fit snugly together, as shown in Fig. 7, an aperture *a* formed by recessing these faces of the barrel and magazine transversely of the same, constituting a means for the reception of the locking pin 19 which is disposed to be projected through the barrel portion 11 of the receiver and thus lock the barrel and magazine securely within and to the receiver, a pivoted bail 20 being carried upon the outer end of the pin 19, as shown in Fig. 1, and compressible within the recessed portion 21 when the fire-arm is in operable condition. It will thus be seen that the barrel 12 and magazine holding tube 13 are readily detachable from the receiver by simply removing the pin 19, and in order to retain the barrel 12 and the magazine holder 13 in proper connected relation when detached and also to assist in bracing the same when in attached position, the embracing member 22 is connected to and surrounds the forward end of the magazine tube 13 and is held relatively thereto and upon the barrel 12 by means of the metal strap 23, the same being reduced to prevent any interference with the sighting of the fire-arm,

The magazine retaining tube 13, as clearly shown in Figs. 5 and 6, is provided with the magazine receiving and enlarged bore 24 which terminates in the reduced bore 25 forming the directing entrance into the receiver, the catch 26 pivoted at 27 being carried by the tube 13 with its cartridge engaging lug 28 normally held by the spring 29 projected within the bore 25 and in the path to engage the cartridge C, the trigger or releasing end 30 of the catch 26 being projected within the recessed portion 31 of the tube or sleeve 13 and in the path of the spring actuated plunger 32 which is mounted within the bore 33 formed parallel or

nearly so with the bore 25 and sealed with the plug 35. This plunger 32 carries the pin 34 which, due to the spring 36, is normally projected toward the catch 26, the purpose of which will presently appear.

The detachable and flexible magazine 43 is used in connection with the tube 13, and thus renders the necessity of the introduction of the cartridges C through the apertures 9—10 of the receiver into the bore 25 of the tube 13 unnecessary, as my number of these magazines may be loaded, and the empty one removed to be replaced by a filled one. In the outer end of the magazine is attached the plug 37, which as shown has mounted therein a pivoted lever 38 having the operating button 39 exteriorly of the plug 37, the spring 40 being provided to normally hold the lever 38 and the locking pin 41 in the position as shown in Fig. 5, so as to engage the annular slot 42 in the outer end of the tube 13 and thus lock the magazine 43 within the tube 13 and against outward displacement. The body portion of the magazine 43 is preferably made of coiled flat wire thus providing a flexible cartridge holder, the same being reinforced by the intermediate bands 44 and 45 and the longitudinally disposed stiffening wires 46' which are connected at their ends to the plug 37 and the band 45 and threaded through the band 44 or between the band 44 and the coiled portion of the magazine. Connected to the band or sleeve 45 and projecting forwardly therefrom, is a flat metal guiding arm 46 and a longer cartridge retaining and guiding arm 47. The forward ends of these guiding arms 46 and 47 are disposed for sliding movement at diametrically opposite points within the cartridge directing band or sleeve 48 which is mounted for inward sliding movement upon the extreme exit end of the magazine 43. The free end of the metal arm 47 is inturned as at 49 and projects to engage the rim of the respective cartridges and retains the last one within the magazine, while when the magazine is empty as shown in Fig. 6, the end 49 engages the headed portion 50 of the cartridge ejecting pin or stud 51 to prevent the too far extension of the same without the magazine and to thus limit the extension of the operating spring 52 of the ejector 51, said spring 52 being disposed within the magazine 43 and abutting the inner end of the plug 37, as shown in Fig. 5.

In order to permit the introduction of a cartridge within the rear end of the magazine 43 when the same is within the tube 13, the trap 53 is provided, the same being pivoted upon a pin 54 within the recessed portion formed in the side wall of the tube 13, its lug 55 being abutted by the spring 56 to normally hold the trap 53 in the position as shown in Fig. 6, but permitting the same

to be drawn outwardly and exteriorly through the slots 9-10 so that the cartridge may be inserted within the bore 25 and the magazine 43, the bullet end of the cartridge being disposed against the outer end of the ejector 51.

In order to provide a means to prevent the falling out of the cartridge C when it is in the position as shown in Fig. 5, and after the magazine 43 has been removed and before the insertion of a filled one, the catch 57 is pivoted upon the pin 58 and is bodily carried by the tubular member 13 in one wall thereof, the spring 59 being disposed to hold the cartridge rim engaging end 60 projected within the bore 25 when the tube 13 is detached from the receiver, the engagement of the receiver with the catch 57 depressing the spring 59 and removing the hooked end 60 out of the bore 25 to the position as shown in Fig. 6 when the parts are assembled.

Mounted for resilient tilting and swinging movement within the forward portion of the receiver, is the cartridge receiver and elevator 61, particularly set forth in detail and in perspective in Figs. 22 and 23, the same being provided with the transverse elongated slot or aperture 87 therethrough for surrounding the pin 88 bridging the receiver and forming the pivoting means for the elevator 61. The free end of the leaf spring 62 is seated within a recess 63 upon the under side of the elevator and forwardly of the pivoting pin 88 and thus tends to elevate the forward end of the elevator from the position as shown in Figs. 1 and 5 to that shown in Fig. 2. The upper surface of the elevator 61 is recessed as at 64 for the reception of the cartridge as shown in Fig. 5, the bridging portion 65 forming a guiding means for the pin 66 which extends and slides longitudinally of the elevator 61 at the bottom of the cartridge receiving portion thereof and has its catch end 67 normally projected by the pin 68 and spring 69 into engagement with the projected end of the pin 34, to thus lock the elevator in the position as shown in Fig. 5 and against accidental upward movement. The opposite end of the rod or pin 66 is attached by means of the pin 72 to the cartridge abutting plate 71, said plate 71 being pivoted at 70 transversely of the rear end of the elevator 61 and for engagement with the base of the cartridge as clearly shown in Fig. 5, so that the action of the spring 52 upon the various cartridges within the magazine and within the bore 25, will tend to push upon the cartridge within the elevator and thus move the plate 71 rearwardly to retract the pin 66 against the spring 69 and thus release the catch end 67 from the pin 34, so that the manipulation of the breech block 73, as will presently appear, will cause the

movement of the elevator 61 from the position in Fig. 1, to that shown in Fig. 2.

The breech block 73 is provided upon opposite sides with longitudinally disposed grooves 74 which coact with ribs 74' formed upon the inner adjacent faces of the receiver so that the breech block 73 will always be in alignment with the breech end of the barrel 12 and in either position as shown in Fig. 1 or Fig. 2. The forward end of the breech block 73 is provided with the spring clip or cartridge extractor 73', which as the block is moved from the position as shown in Fig. 1 to the position as shown in Fig. 2, engages the rim of the cartridge within the breech of the barrel 12 and carries the same rearwardly to be finally engaged by the ejecting member 75 which is connected to the receiver as shown in Fig. 2 and has its free end 75' disposed to engage the rim at 85 the closed side of the receiver and throw the shell outwardly and through the recessed or slotted portion 8 of the cap or closure 7, thus extracting and ejecting the shell before the introduction of the unused cartridge 90 by the elevator 61.

The under surface of the breech block 73 is recessed at 75^a, Fig. 5, and into this recessed portion is adapted to fit the curved portion 76 of the elevator 61 when in the position as shown in Fig. 5, the forward end of the breech block when in the position as shown in Fig. 2 being disposed to engage the upper rear portion of the cartridge C to move the same from the elevator into the breech of the barrel 12 when the breech block 73 is moved to the position as shown in Fig. 1.

In order to cause the breech block 73, to tilt the elevator 61 from the position of Figs. 1 and 5 to that of Fig. 2, the curved edges 76 of the elevator are contacted by the inclined face 75^a of the breech block during the retracting of the breech block, the elevator being slightly depressed against the spring 62, and so moved that the cartridge carried thereby, after the used shell has been extracted and ejected by the extractor 73' and the hook 75' of the ejector 75, has its base presented in front of the lower front end of the breech block. Thus the forward movement of the breech block to breech closing position will direct the cartridge in the elevator to the barrel 12, and downwardly tilt the elevator, causing it to 115 assume the position of Fig. 5, to receive the next cartridge from the bore 25.

To provide a means to lock the breech block retracted after the last cartridge has left the bore 25, and thus notify the marksman that such is the case, the vertically slideable locking pin 78, is provided, and is disposed, as will presently appear, to enter the recess 77' formed in the projection 77 of the breech block, when the breech block is fully 130

retracted and thus lock the block against closing. To set forth this operation fully, the complete operation from the time the last cartridge leaves the bore 25 and is placed in the elevator 61 and is finally delivered into the breech of the barrel, and is exploded is as follows: When the last cartridge leaves the bore 25, the lever 26, is raised by its spring 29 and its end 30 engages the head 32 and projects the pin 34 beyond the bushing 35 and into engagement with the catch 67, but as the ejector pin 51 is pushing upon the cartridge in the elevator before its delivery to the barrel, the catch 67 is retracted, but is projected when the cartridge is placed in the breech. Thus when the elevator is lowered by the closing breech block, the projected catch 67 engages the projected lock 34 and thus the free front end of the elevator is held against rising. When the breech block is retracted, due to the recoil from the last cartridge within the breech, the engagement of the breech block with the elevator due to the front end of the elevator being locked, causes the rear end of the elevator to be depressed, so that the spring 62 is depressed and the hook 85, of the lever 84, is also depressed, it being in engagement with the elevator through the recess 86. The forked end 82 of the lever 84 is now raised and through the spring 81, elevates the bolt 80, to place the lock 78 in the path to be snapped into the recess 77' of the breech block when the bolt is in the position as shown in Fig. 2, locking the breech block against closing. The empty magazine 43 is now removed from the tube 13 and a filled one inserted, its foremost cartridge being projected into the awaiting elevator and releasing the catch 67, so that the spring 62 elevates the elevator to the position of Fig. 2. The upward movement of the elevator carries the hooked end 85 of the lever 84 upwardly, causing the forked end 82 of the lever 84 to swing down and carry the rod 80. This movement pulls the lock 78 out of the recess 77' of the breech block 73. Thus the upward movement of the elevator automatically releases the breech block permitting it to close and carry with it the cartridge in the raised elevator and place the same in the breech of the barrel 12. However should it be desired to release the breech block to close without loading the barrel, the button 138 is pulled rearwardly to pull the lever 133 which engages the pin 132 and pulls the rod 171 rearwardly and against the tension of its projecting spring 174, moving the recess 175 of the rod 171, from above the projection 79 of the bolt 80, and placing the end 175' into engagement therewith. This depresses the lock 78 and releases the breech block to the action of the spring 105 and it is closed without delivering a cartridge to the barrel. The au-

tomatic retraction of the breech block, due to the cam 77 engaging the projection 79, insures the depression of the lock 78, so that it will not lock the breech block as long as there is a cartridge in the elevator 61.

At the rear under side of the breech block 73, two apertured lugs 89 are provided and through the apertures thereof is disposed the pivoting pin 90 by means of which the forward end of the forward member 91 of the breech block locking device is attached, this breech block locking device being composed of the three members 91, 95 and 97 which when in the position as shown in Fig. 1 will provide a rigid locking means to hold the breech block closed, to be operated, as hereinafter set forth, through the recoil of the breech block 73 and to automatically return the same to breech closing position.

The member 91 is provided with the apertured lug 92 through which projects the pin 93 which provides the pivoting means for the spaced apertured lugs 94 of the intermediate member 95, a pin 96 being disposed transversely through the member 95 intermediate of the ends thereof and forming the pivotal connecting means for the rear member 97 of the breech block projecting and locking device.

The intermediate member 95, as clearly shown in detail in Fig. 8, is provided with the longitudinal bore 98 therethrough, and disposed for sliding movement therewithin is a plunger 99, connected to the resilient rod 100 whose forward looped end is mounted upon the pin 102 between the spaced lugs 101 of the member 91, a retaining disk 103 being disposed within the outer end of the bore 98 and being held in position by means of the spring catch or lock 104. This retaining disk is disposed to retain the spring 105 within the bore 98, so that the action of the spring will normally depress the plunger 99 and thus hold the members 91 and 95 in locked position, as shown in Figs. 1 and 8, with the abutting faces 106 and 107 of the members 91 and 95 in contact to limit the upward movement of the members 91, 95 and 97 when in the position as shown in Fig. 1. The projecting end 108 of the member 95 is disposed for movement between the spaced end of the member 97 so that the movement of the members 91 and 95 from the position as shown in Fig. 1 to that shown in Fig. 2, when the two members 91 and 95 are moved, will be downwardly or flexed.

The member 97 is provided with the elongated slot 109, through which is projected the fixed pin 110 carried by the receiver 2 and which provides a means for limiting and directing the movement of the member 97. Disposed within the slot 109 between the forward end thereof and the pin 110, is a spring 111, which normally tends to

hold the member 97 in the position as shown in Fig. 2 or forwardly within the receiver.

Mounted in and carried by the breech block 73 is the spring retracted firing pin 112, the enlarged hammer receiving end 113 being mounted within the bore 113' of the breech block, and so that the spring 114 therewithin exerts a tension to normally hold the hammer receiving end of the pin 113 exteriorly of the breech block, as clearly shown in Fig. 4. The two parallel bores 115 are provided within the breech block 73 one upon each side of the firing pin, and disposed for sliding movement therewithin are the plungers 116 connected to the inner ends of the hammer guiding and actuating arms 117, the same passing through the reduced apertures 118 of the breech block 73 and carrying upon their outer free ends, the hammer block 119. The springs 116 are disposed upon the rods 117 within the respective bores 115 between the rear end of the same and the plungers 116, and thus exert a normal tension to hold the hammer 119 toward and into violent engagement with the pin 113 to operate the firing pin to explode the fulminating cap of the cartridge C. An arm 120 is connected to and carried by the hammer 119 at one side thereof, being guided in its sliding movement by a groove formed in the receiver 2, the same having formed upon its free end, at the under side thereof a hook or catch 121 disposed to engage the hooked end 122 of the trigger actuated lever 123. This trigger actuated lever 123 is pivoted as at 124 to the receiver and has its downwardly projecting arm 125, which is formed at right angles to the arm 123 as clearly shown in Fig. 11, provided with the trigger engaging lower end 126 and with the flat spring 127 which normally exerts a tension to hold the arm 125 outwardly from the receiver wall and in the path to be engaged by the lug 128 carried and actuated by the trigger 129. The trigger 129 is mounted for movement upon the pin 130 carried by the receiver 2 at a point intermediate of its ends and near the forward portion of the slot 4 of the receiver.

In order to provide a safety means whereby the actuation of the trigger 129 will be ineffective as regards the arm 123, a rounded shoulder or cam 131 is formed upon the arm 125 and is disposed in the path to be engaged by the prong 132 of the lever 133, said lever 133 being disposed within the rear portion of the receiver and pivoted upon the pin or shaft 134 mounted in the receiver. The upper end 135 of the lever 133 is fitted within the bail 136 projecting through the elongated slot 137 of the receiver near the hand grip portion thereof, and carried by the pivoted button 138 whose lower end is mounted upon the extreme

outer end of the pin 134 so that the button 138 and lever 133 will have the same axis. As shown in Figs. 3 and 4, this button 138 is disposed within the angular recessed portion 139 formed in the receiver 2, the button being held against outward displacement by means of the detachable plate 140 and normally held in intermediate or operating position as shown in Fig. 3 by means of the small spring 141 in Fig. 3. Thus the movement of the button 138 to the rear of the slot 139 against the tension of the spring 141, will operate the finger 132 to depress the arm 125 and thus move the end 126 thereof out of the path to be engaged by the lug 128 of the trigger 129, thus permitting the actuation of the trigger without operating the arms 125 and 123 and releasing the hammer 119. When the button 138 is in the forward position as shown in dotted lines in Fig. 3, the movement of the trigger 129 will cause the lug 128 to engage the end 126 of the arm 125, thus moving the same upwardly and to the rear upon its pivot 124 to release the hooked end 122 from engagement with the hook 121 which action releases the hammer 119 to the action of its springs so that the firing pin is propelled to cause the explosion of the cartridge C disposed within the breech of the barrel.

In order to provide a means for assisting in the downward flexing of the members 91 and 95 of the breech block locking device, and also to act as a spring buffer for the hammer 119 and breech block 73 when both are propelled rearwardly by the action of the exploded cartridge, a plate 142, as shown in detail in Fig. 12, is provided, the same being attached to the under surface of the top of the receiver at the intermediate portion thereof. This plate 142 has depending therefrom the curved lug 142', which is disposed in engagement with the curved portion 95' of the member 95, so that as the breech block 73 is moved rearwardly due to the recoil of the exploding cartridge, the members 91, 95 and 97 will also be moved rearwardly against the tension of the spring 111, this action causing the curved surface 95' to ride upon the curved surface 142' and thus start the projecting members 91 and 95 from the position as shown in Fig. 1 to that shown in Fig. 2, the continued rearward movement of the breech block 73 causing the members 91 and 95 to assume the position as shown in Fig. 2 and consequently the compression of the spring 105 carried by the member 95. The buffer block 143 is carried upon the forward upper face of the lug 142', and has its pin slidably mounted therein, the spring 145 being disposed upon the pin 144 between the adjacent faces of the lug 142' and the buffer block 143, said buffer block 143

143 being disposed in the path to be engaged by the rear face of the hammer 119 as clearly shown in Fig. 2. It will be seen that when the parts are moved to this position, the hooked end 121 of the arm 120 will be carried rearwardly and slide upon and engage the hooked end 122 of the hammer locking arm 123 so that when the breech block 73 and the flexing members 91 and 95 are moved, due to the spring 105, from the position shown in Fig. 2 to that shown in Fig. 1, that the hammer 119 will be held against the tension of its springs, or in the position as clearly shown in Figs. 1 and 4. 10 As before described, this action also causes the actuation of the cartridge elevator 61 from the position as shown in Fig. 1 to that shown in Fig. 2 and again to that position as shown in Fig. 1, the elevator thereby lifting the cartridge from the mouth of the magazine and presenting the same to the breech of the barrel 12 so that the projection of the breech block 73 into breech closing position will cause the cartridge to be seated within the breech of the barrel and the consequent depression of the elevator 61 from the position shown in Fig. 2 to that shown in Fig. 1.

As it is desirable that the breech block 73 be manually retracted to permit of the introduction of the first cartridge within the breech of the barrel 12, a pin 146 forms the medium for connecting the forward end of the rod 147 to the member 95 of the breech block actuating device, said rod being extended rearwardly and above the closure plate 5 of the receiver. The pin 148 is carried by the rear end of the rod 147, and has disposed thereupon the two anti-frictional rollers 149 so that a means is provided for anti-frictionally guiding the rod 147 during the flexing and straightening of the members 91 and 95, and also provides a means whereby the rod 147 may be pulled upon to flex such members and retract the breech block 73. In order to accomplish this, the spaced upper end 151 of the lever 158 is pivoted upon the pin 130 and astride of the projection 128 of the trigger 129, so as to not interfere with the manipulation of the trigger 129, while pivoted upon each side of the lever 158 intermediate of its ends, as at 152, are the two links 153. The lower ends of these links 153 are secured by means of a pin 154 intermediate of the ends of the hand lever 155, said lever 155 being pivoted at 156 to the receiver so as to have movement to and from the lower portion of the receiver, with its free end 157 disposed adjacent to the hand grip portion of the stock and in ready access to the marksman. The lower end of the lever 158 is connected by means of a pin 158' to the lower end of the arm 159, said arm 159 being grooved as at 160 so that the

arm may slidably ride upon the rod 147 and in turn so that the rod 147 may slidably ride in the groove 160 of this arm. Carried by the upper end of this arm 159 are the two oppositely disposed anti-frictional rollers 161 which are disposed, when the lever 165 is moved upwardly to the position as shown in Fig. 3, to engage the anti-frictional rollers 149 and pull upon the rod 147 to manually move the pivoted members 91 and 95 from the position shown in Fig. 1 to that shown in Fig. 2. Thus it will be seen that a manual means for causing the actuation of the breech block 73 is provided, the parts being presented to their locked and breech closing position by the action of the spring 105 upon the plunger 99.

In order to lock the lever 155 against accidental upward movement and against the manual manipulation of the breech block 73, a pin or rod 162 is pivoted to the end 157 of the lever 155, and projects upwardly through the vertical slot 163 formed in the extreme rear portion of the receiver, the same, as shown in Fig. 21, being provided with the recessed portion 164 adjacent its upper end and in the path to be engaged by the locking bolt 165 slidably mounted within the block 167 mounted within the receiver and forming the abutting and guiding means for the rollers 148 of the rod 147. Mounted upon the pin or lock 165 within the block 167 is a spring 166 which normally holds the lock 165 in the position as shown in Fig. 2 and consequently seated within the recess 164 of the arm or pin 162. Thus when in this position, the lever 155 is held against movement toward or from the receiver of the fire-arm.

In order to manipulate the lock 165 to release the arm or pin 162 to permit of the movement of the lever 155 from the position shown in Fig. 2 to that shown in Fig. 3, the forward end of the lock 165 is provided with the hooked terminal 169 which is disposed in the path to be engaged by the reduced end 170 of the lever 133, this action occurring when the button 138 is moved to the rear of the recess 139.

From the foregoing description, taken in connection with the drawings, it is evident that an automatic repeating fire-arm constructed according to and embodying the present invention, has elements which permit of the rigid securing of the barrel to the receiver and stock so that the relative position of the magazine, barrel, receiver and stock are maintained at all times, the only movable parts that retain the cartridge seated within the breech of the barrel being the breech block 73 and the locking and projecting device composed of the members 91, 95 and 97. It is also evident that the recoil from the exploding cartridge will cause a slight retraction of the breech block 73.

which will transmit motion to the members 91, 95 and 97 causing the slight depression of the spring 111, the movement of the member 95 against the curved lug 142', causing the members 95 and 91 to be deflected or moved downwardly, giving a cushion action to the breech block due to the compression of the spring 105, the ejector 75 being brought into place to eject the used shell 10 carried rearwardly by the breech block 73 so that the elevator 61 with the new cartridge may be properly positioned to place the cartridge with the bullet end toward the breech of the barrel 12, the same being 15 forced home within the breech upon the projection of the breech block 73 due to the action of the compressed spring 105 in straightening the members 91 and 95 from the position as shown in Fig. 2 to that shown 20 in Fig. 1. It is also evident that when the elevator has been moved from the position shown in Fig. 2 to that shown in Fig. 1, that the next cartridge within the bore 25 due to the spring 52 will be moved out of 25 the bore 25 into the receptacle of the elevator 61, its base being projected against the pivoted plate 71 so that the catch rod 66 will be released from the catch rod 34 of the tube 13, the elevator being held in the 30 position shown in Fig. 5 by the closed breech block 73 and in ready position for elevating the cartridge upon the retraction of the breech block and the ejection of the used shell from the receiver.

35 What is claimed is:

1. An automatic repeating firearm, having a receiver, a barrel, a magazine, a trigger, a breech block slidably mounted in the receiver for an alined movement to and from the barrel, a plurality of hingedly connected members constituting a lock for the breech block and a means for retracting and projecting the same connected to the breech block and mounted within the receiver, said 40 members being flexed due to the effect of the recoil of an exploding cartridge upon the breech block, a spring propelled hammer, a cartridge elevator mounted in the receiver and operably connected to the breech block, 45 manually operable means for flexing the hinged members to retract the breech block, means disposed in the path of and above the hinged members for engaging and flexing the same during the retraction of the breech block, manually operable means for rendering of the elevator inactive during the 50 manual retraction of the breech block, a spring actuated lock for rendering inactive the manually controlled flexing means, 55 manually operable means for actuating said lock to permit the actuation of the breech block flexing means, and means for locking the elevator in cartridge receiving 60 position operable after the last cartridge has 65 been delivered to the barrel.

2. An automatic repeating fire-arm, having a receiver, a barrel, a magazine, a trigger, a slidable breech block in the receiver, a hammer carried by the breech block, a firing pin, an L-shaped sear for holding the hammer set, one terminal of the sear being movable transversely of the receiver, and a sear lock for moving the transversely movable terminal of the sear into and out of the path of the trigger. 70

3. An automatic repeating fire-arm, having a receiver, a barrel, a magazine, a trigger, a slidable breech block in the receiver, a hammer carried by the breech block, a firing pin, an L-shaped sear for holding the hammer set, one terminal of the sear being movable transversely of the receiver, and a pivoted sear lock for moving the transversely movable terminal of the sear into and out of the path of the trigger. 80

4. An automatic repeating fire-arm, having a receiver, a barrel, a magazine, a trigger, a slidable breech block in the receiver, a hammer carried by the breech block, a firing pin, an L-shaped sear for holding the hammer set, one terminal of the sear being movable transversely of the receiver, a sear lock for moving the transversely movable terminal of the sear into and out of the path of the trigger, manually operated means for retracting the breech block, and a lock therefor operably connected to the sear lock. 90

5. An automatic repeating fire-arm, having a receiver, a barrel, a magazine, a trigger, a slidable breech block in the receiver, a hammer carried by the breech block, a firing pin, an L-shaped sear for holding the hammer set, one terminal of the sear being movable transversely of the receiver, a pivoted sear lock for moving the transversely movable terminal of the sear into and out of the path of the trigger, manually operated means for retracting the breech block, and a lock therefor released when the sear is locked and locked when the sear is unlocked. 100

6. An automatic repeating fire arm, having a receiver, a barrel, a magazine, a spring elevated cartridge carrier, a breech block mounted for automatic opening due to the recoil of an exploding cartridge, a spring for closing the breech block, a vertically movable spring projected pin in the path to engage the breech block for locking the breech block open, said pin being provided 115 with a projection intermediate of its ends, means controlled by the carrier and active when the empty carrier is elevated to hold the pin and breech block in locking position, and a manually operable slidable rod disposed to engage the projection of the pin, said rod when manually actuated depressing the pin to release the breech block. 120

7. An automatic repeating fire-arm, having a receiver, a barrel, a breech block slid- 125

able in the receiver, a flexing member mounted in the receiver and connected to the breech block and forming a means to lock, retract and project the breech block, 5 and means for manually flexing the member to retract the breech block, said last means including a hand lever pivoted to the receiver, an arm pivoted to the lever and projecting for sliding movement in the receiver, 0 and a rod connected to the flexing member and the end of the arm within the receiver.

8. An automatic repeating fire-arm, having a receiver, a barrel, a breech block slideable in the receiver, a flexing member 5 mounted in the receiver and connected to the breech block and forming a means to lock, retract and project the breech block, means for manually flexing the member to retract the breech block, said last means including a hand lever pivoted to the receiver, 0 an arm pivoted to the lever and projecting for sliding movement in the receiver, a rod connected to the flexing member and threaded through the end of the arm within the receiver, and coöperating means carried by the rod and the arm, whereby the rod is connected to the arm to cause the flexing of the members when the lever is manually operated.

9. An automatic repeating fire-arm, having a receiver, a barrel, a breech block slideable in the receiver, a flexing member mounted in the receiver and connected to the breech block and forming a means to 5 lock, retract and project the breech block, means for manually flexing the member to retract the breech block, said last means including a hand lever pivoted to the receiver, and means for locking the lever against 0 manual manipulation.

10. An automatic repeating fire-arm, having a receiver, a barrel, a breech block slideable in the receiver, a flexing member mounted in the receiver and connected to 5 the breech block and forming a means to lock, retract and project the breech block,

means for manually flexing the member to retract the breech block, said last means including a hand lever pivoted to the receiver, and automatically locked and manually released means for controlling the lever. 50

11. An automatic repeating fire-arm, having a receiver, a barrel, a breech block slideable in the receiver, a flexing member mounted in the receiver and connected to 55 the breech block and forming a means to lock, retract and project the breech block, means for manually flexing the member to retract the breech block, said last means including a hand lever pivoted to the receiver, 60 automatically locked and manually released means for controlling the lever, an arm pivoted to the lever and projecting for sliding movement in the receiver, and a rod connected to the flexing member and the end of 65 the arm within the receiver.

12. An automatic repeating fire-arm, having a receiver, a barrel, a breech block slideable in the receiver, a flexing member mounted in the receiver and connected to 70 the breech block and forming a means to lock, retract and project the breech block, means for manually flexing the member to retract the breech block, said last means including a hand lever pivoted to the receiver, 75 automatically locked and manually released means for controlling the lever, an arm pivoted to the lever and projecting for sliding movement in the receiver, a rod connected to the flexing member and threaded through 80 the end of the arm within the receiver, and coöperating means carried by the rod and the arm, whereby the rod is connected to the arm to cause the flexing of the member when the lever is manually operated. 85

In testimony that I claim the foregoing as my own, I have hereto affixed my signature in the presence of two witnesses.

ADOLPHUS C. MCCLURE.
